UNITED STATES PATENT OFFICE.

JAMES W. DANIELS, OF PATERSON, NEW JERSEY.

SNOW AND ICE MELTER.

SPECIFICATION forming part of Letters Patent No. 782,191, dated February 7, 1905.

Application filed April 21, 1904. Serial No. 204,188.

To all whom it may concern:

Be it known that I, JAMES W. DANIELS, a citizen of the United States of America, and a resident of Paterson, in the county of Passaic and 5 State of New Jersey, have invented certain new and useful Improvements in Snow and Ice Melters, of which the following is a specification.

This invention relates to certain new and 10 useful improvements in snow and ice melting machines of that class wherein the snow is taken up by a shovel or other means and delivered to a conveyer or carrier and by the latter delivered to a tank or receptacle where it 15 is melted by artificial heat properly applied.

The present invention has for its objects, among others, to provide an improved device of this general character by which the collection and melting of the snow may be more successfully and rapidly accomplished.

A further object is to provide a machine of this class which shall be capable of performing the same functions whether going in one direction or the other. In other words, the 25 machine as preferably constructed is a double-end, being equipped alike at both ends, for an obvious purpose.

Still a further object is to provide for the inclosure of the carrier and the tank and the 30 heating devices, whether they be gas, gasoline, crude oil, electricity, or any other artificial heating appliances.

Still a further object is to provide means whereby the snow or ice as it is being carried 35 through the machine shall be broken up, thus facilitating its melting. This breaking means is disposed above the carrier, and the heating devices are so disposed as to act to the best advantage on the snow. The carrier extends 40 the whole length of the machine, and the same carrier serves with both shovels and being operated through the same medium no change whatsoever is necessary in the mechanism except the reversal of the direction of movement of the machine.

Other objects and advantages of the invention will hereinafter appear, and the novel features thereof will be specifically defined by the appended claims.

50 The invention in its preferred form is clearly

illustrated in the accompanying drawings, which, with the numerals of reference marked thereon, form a part of this specification, and in which—

Figure 1 is a side elevation of a snow and 55 ice melting machine constructed in accordance with my invention. Fig. 2 is a plan view with a portion broken away. Fig. 3 is a vertical cross-section taken on the line 3 3 of Fig. 1. Fig. 4 is an end elevation of the same. Fig. 60 5 is a perspective view of the machine complete. Fig. 6 is a detail plan of the carrier or chain.

Like numerals of reference indicate like parts throughout the several views. 65

Referring now to the drawings, 1 designates the truck or frame mounted on suitable wheels 2 on axles 3 and designed to be either self-propelled or moved by an electric car, locomotive, or other suitable motive power. When 70 self-propelled, the fuel supply will be carried upon the machine; but when otherwise propelled it is designed to have the fuel carried by the car that moves the machine and the fuel conducted to the burners of the machine 75 by suitable piping. In the present instance the machine is shown and will be described as of the latter type. The carrier is designed to be moved through a casing or housing 4, through the roof 5 of which extend the smoke-stacks 80 6, as clearly shown in the drawings, for an obvious purpose.

At each end of the machine is a shovel 7, pivotally mounted, as at 8, (see Fig. 1,) and this shovel is designed to be raised and lowered, as occasion may require, by suitable means—such, for instance, as a drum 9 on a shaft 10, mounted in a suitable standard 11 at the end of the machine just behind the dashboard 12, and upon this drum are wound the 85 chains 13, attached to the shovel, one near each side, as seen in Fig. 4 at 14. This shaft is provided with a hand-wheel 15, by which it may be turned, and a suitable ratchet-and-pawl device is provided, as seen at 16, to hold 90 the shovel in its adjusted position.

It is to be understood that the machine is designed, primarily, to run upon a railroad-track.

At the sides of the shovel at points which 100

will lie outside the track are brackets 17, in which are swiveled the small rollers 18, designed to travel upon the ground.

19 is a shaft mounted in the side walls or 5 braces of the shovel, and on each of these shafts is a roller 20, and around these rollers passes the carrier 21, which passes also over idlers 22 and over sprocket-wheels 23, which latter are mounted inside the housing or casing 4 and carried by shafts 24, mounted in suitable bearings 25, as seen clearly in Figs. 1 and 5. This carrier may be of any suitable 10 form of construction suited to the purpose, in this instance being shown as composed of a series of slats 26, suitably connected to the carrier-chains 27, one at each end of the slats, and designed to coöperate with the sprocket-wheels 23, there being a sprocket-wheel at 15 each side of the machine and near each end of the tank within said casing, as seen best in Fig. 1. As will be readily understood from Fig. 1, this carrier extends the whole length of the casing, the top and bottom portions running horizontally and parallel over and 20 between the sprocket-wheels and from thence downward toward each end of the machine. Beneath the carrier between the sprocket-wheels is a tank or receptacle 28, designed to 25 receive the water as the snow and ice becomes melted, and this tank is provided with a suitable hose 29, whereby the water may be discharged therefrom when desired.

Within the casing 4 are the burners 30, of any suitable or well-known character. In this 35 instance they are shown as of that type designed for burning gasolene or the like, fuel-oil, or any suitable fuel. They are disposed to extend substantially the entire length of the space over the tank and are all connected with 40 a common supply-pipe 31, as seen clearly in Fig. 3, and to which is connected the supply-pipe 32, as seen in Figs. 3 and 5, which supply-pipe is designed for connection with a source of fuel-supply (not shown) which will 45 be carried on the motor-car. The carrier runs above and below these burners, as will be readily understood.

33 represents rakes disposed above the sprocket-wheels, as seen in Figs. 1 and 3, and 50 are for the purpose of cutting up the snow as it is carried along by the carrier, and for the purpose of more thoroughly cutting the snow these rakes are disposed so that their teeth shall be staggered, as seen in Fig. 3.

55 34 represents an opening for the supply of air to support combustion.

Motion is imparted to the carrier when the machine is constructed as a four-wheel truck by means of gearing, as seen clearly in the 60 different views. Referring to Fig. 5, it will be noted that on each axle there is at each end a gear-wheel 35, which is designed to mesh with a smaller gear-wheel 36 on the shafts of the sprocket-wheels, as seen also in Fig. 1 and in plan in Fig. 2. In an eight-wheeled

truck an independent motor for actuating the carrier may be employed.

The machine is provided at each end with a suitable coupling, so that it may be readily connected with another car or a locomotive or 70 other source of motive power.

With the parts constructed and arranged substantially as above described the operation will be readily understood from the foregoing description, especially when taken in 75 connection with the annexed drawings. Briefly stated, it is as follows: As the machine is propelled by any suitable power the shovel entering the snow throws the same onto the carrier, which takes it up, and as it passes beneath the rakes the snow is cut up, so as to be more easily melted by the heat from the burners, (or electricity may be the source of heat,) which heat is sufficient to melt the snow while it is being carried over the burners. The 80 water falls into the tank, from which it may be discharged when necessary. The carrier and burners all being inclosed and the heat located beneath the carrier while it is moving the snow into the path of the heat from the 85 burners enables me to secure the best results and insures the melting of the snow as fast as it is delivered to the machine and over the burners.

While the structural embodiment of my invention as hereinbefore described and shown is what I at the present time consider the preferable one, it is evident that the same is subject to changes, variations, and modifications in various ways without departing from the 90 spirit of the invention or sacrificing any of its advantages. I therefore do not wish to be restricted to the details of construction herein disclosed, but reserve the right to make such changes, variations, and modification as come 95 properly within the scope of the protection prayed.

What is claimed as new is—

1. In a snow and ice melter, a supporting-truck, a shovel at each end thereof, a carrier mounted upon both and adapted to serve with either of said shovels, and a heater.

2. In a snow and ice melter, a supporting-truck, a shovel at each end thereof, a carrier mounted on both and adapted to serve with either of said shovels, and a heater, the said carrier being mounted to travel above and beneath the heater.

3. In a snow and ice melter, a supporting-truck, a shovel at each end thereof, a carrier mounted on both and adapted to serve with either of said shovels, a tank, and heaters intermediate the carrier and tank.

4. In a snow and ice melter, a supporting-truck, a shovel at each end thereof, an endless carrier having bearings in both of said shovels and adapted to serve with either thereof, a heater, a tank and a casing inclosing the heater and carrier.

5. In a snow and ice melter, a supporting-

truck, a shovel at each end thereof, an endless carrier extending from shovel to shovel and mounted at opposite ends of the truck in opposite shovels and adapted to serve with either, 5 a tank, a heater arranged above the tank and adapted to heat the snow as it is upon the carrier, and a casing for the carrier and heater.

6. In a snow and ice melter, a supporting-truck, a shovel at each end thereof, an endless carrier mounted at opposite ends of the truck 10 on said shovels to travel the whole length of the truck and to serve with either of said shovels, means for actuating the carrier, means for heating and melting the snow while it is being carried through the machine, and a receptacle 15 for collecting the water.

7. In a snow and ice melter, a supporting-truck, a shovel at each end, an endless carrier adapted to serve with either shovel, means including 20 burners for melting the snow as it is being carried through the machine, and means located above the burners and tank for cutting the snow while it is being moved by the carrier.

8. In a snow and ice melter, a supporting-frame, a shovel at an end thereof, a carrier co-operating with said shovel, a receptacle for the water, a heater, means located above said receptacle and heater for cutting the snow while it is being moved by the carrier, and an inclosing 25 casing therefor.

9. In a snow and ice melter, a supporting-truck, a shovel at an end thereof, a carrier mounted in and adapted to serve with said shovel, a heater located below the upper travel 30 of said carrier, stationary means located above the heater and above the carrier for cutting the snow, and a receptacle for the water.

10. In a snow and ice melter, a supporting-truck, a shovel at each end thereof, an endless carrier mounted at opposite ends of the ma- 40

chine on said shovels and adapted to serve with said shovel, means for actuating the carrier, a heater disposed below the upper travel of the carrier, a receptacle for the water, and a casing inclosing the heater and carrier. 45

11. In a snow and ice melter, a supporting-frame, a shovel at an end thereof, an endless carrier mounted in said shovel to serve therewith, means for vertically adjusting the shovel, and a heater disposed to heat the snow as it is moved 50 through the machine by the carrier, and means for cutting the snow as it is being moved through the machine by the carrier, said cutting means being located above the heater and above the carrier. 55

12. In a snow and ice melter, a supporting-truck, a shovel at an end thereof, means for vertically adjusting the shovel, an endless carrier mounted in said shovel and adapted to serve therewith, means for melting the snow 60 as it is being moved through the machine by said carrier, and a device located above the melting means and arranged to coöperate with the carrier for cutting the snow.

13. In a snow and ice melter, a supporting-truck, a shovel at an end thereof, means for adjusting the shovel, an endless carrier, a fixed cutting device arranged above the carrier, heaters disposed to melt the snow as it is being moved through the machine by said carrier, 70 means for actuating the carrier, a receptacle for the water, and a casing inclosing the carrier and the heaters, said cutting device being arranged above the heaters and receptacle.

Signed by me at Washington, District of Columbia, this 20th day of April, 1904.

JAMES W. DANIELS.
